UNITED STATES PATENT OFFICE.

JACOB BETTS, OF NEW YORK, N. Y.

SUSPENDER-END.

SPECIFICATION forming part of Letters Patent No. 248,394, dated October 18, 1881.

Application filed August 11, 1881. (No model.)

To all whom it may concern:

Be it known that I, JACOB BETTS, a citizen of Austria, residing at New York, in the county and State of New York, have invented new 5 and useful Improvements in Suspender-Ends, of which the following is a specification.

This invention relates to the construction of the attaching-piece of suspender-ends; and it consists in an attaching-piece formed of a flat 10 sheet-metal tube, which is provided with detaining-teeth on both its lower and vertical edges adapted to grasp the end inserted in the tube, and with a closing lip or lips on its upper edge for hiding the upper extremities of 15 the end. The sheet-metal tube is also provided with barbs in the body thereof, adapted, like the teeth, to grasp the end inserted in the tube.

This invention is illustrated in the accompanying drawings, in which Figure 1 represents 20 a side view; Fig. 2, a longitudinal section; Fig. 3, a cross-section; Fig. 4, a top-end view; Fig. 5, a bottom-end view.

Similar letters indicate corresponding parts. 25 The letter A designates the body of the sheet-metal tube composing the attaching-piece; b c, its teeth; d, the lips, and e the barbs thereof. The tube A is flat and diverges toward its lower edge, like the ordinary attaching-piece of suspender-ends, and it is moreover formed with 30 a hook, f, or an eye or other device for hanging the whole upon the buckle of a suspender. The teeth b are on the lower edge of the tube, those on one side alternating with those on the 35 opposite side thereof, and the teeth c are on the vertical edges of the tube, while the lips d are on its upper edge, and the barbs e in the body thereof. The teeth b c, as well as the barbs e, have sharp points, and the upper portion 40 of the suspender-end, having been inserted in the tube, the latter is compressed thereon, whereby the teeth and barbs are made to grasp the end, thus firmly holding it in place.

The barbs e are struck up in the body of the tube in a suitable manner, and may be formed 45 either before or after the end is inserted therein. The lips d are two in number, and are of suitable shape to close the upper end of the tube, so that by their means the upper extremities of the suspender-end are effectually 50 hidden from view, which is important, since such extremities usually are raw-edged, and, if visible, impart to the article an unfinished appearance.

It is obvious that the purpose of the lips d 55 can be accomplished by a single lip.

I do not claim an attaching-piece for suspender-ends consisting of a sheet-metal blank bent to form sockets, the body portions of which are furnished with barbs which are 60 pressed inward to bite the suspender-ends within the sockets; nor do I broadly claim an attaching-piece for suspender-ends consisting of a plate having wings to clasp around the suspender-ends, the vertical adjacent edges of 65 said wings being furnished with teeth for engaging the suspender-ends; but

What I claim as new, and desire to secure by Letters Patent, is—

An attaching-piece for suspender ends consisting of a flattened sheet-metal tube, A, formed with the laterally-bent lip or lips d at its top for closing the upper end of the tube, the inwardly-projecting teeth b b, on opposite sides of its bottom edge, and the inwardly-projecting teeth c c along its vertical adjacent edges, all substantially as herein shown and described.

In testimony whereof I have hereunto set my hand in the presence of two subscribing 80 witnesses.

JACOB BETTS.
